Inventor,

Edward Culotta,
By Frederick V. Winters,
Attorney.

UNITED STATES PATENT OFFICE.

EDWARD CULOTTA, OF RICHMOND HILL, NEW YORK.

SPOT TRIMMING FOR DRESSES.

Application filed February 18, 1922. Serial No. 537,613.

To all whom it may concern:

Be it known that I, EDWARD CULOTTA, a citizen of the United States, residing at Richmond Hill, in the county of Queens and State of New York, have invented certain new and useful Improvements in Spot Trimmings for Dresses, of which the following is a full, clear, and exact specification.

10 This invention relates to trimmings for ladies' dresses, and has for its object to provide an improved and cheaper form of spot trimming.

15 Metallic spots are extensively used for trimming, and as heretofore made said spots consist of dome shaped metal heads or spots having spurs for fastening them to dress goods. The present invention contemplates making the heads or spots of celluloid or 20 other suitable plastic material or substance, and mounting them on metallic backing plates having spurs for connecting to the dress goods. The backing plates also have spurs for fastening the celluloid or other 25 heads permanently thereto.

The invention will be first hereinafter described in connection with the accompanying drawings, which constitute part of this specification, and then more specifically defined in the claims at the end of the description.

30 In the accompanying drawings, wherein similar reference characters are used to designate corresponding parts throughout the several views:—

35 Figure 1 is a plan view of a backing plate blank such as may be used in the manufacture of my improved spot trimming.

40 Figure 2 is an edge view of the same.

Figure 3 is a sectional view of the backing plate with its two sets of spurs bent into position for attaching to the head and dress goods, respectively.

45 Figure 4 is a similar section of the completed spot trimming having the celluloid or plastic head molded thereon.

Figure 5 is a side view of the spot trimming.

50 Figure 6 is a sectional view of a backing plate of modified form, and the head attached thereto, the attaching position of the spurs to engage the dress goods being indicated in dotted lines.

Figure 7 is a plan view of a backing plate 55 blank of modified form, and

Figure 8 is an elevation of one of the completed spots attached to a piece of dress goods, the latter being shown in section.

Referring first to Figures 1 to 4, inclusive, the metallic backing plate 1 is preferably made round with crossing slits 2 at the center for forming the upstanding spurs 4 of Figures 3 and 4. The blank also has spurs 3 projecting from the periphery of 65 the circular plate 1, said spurs being bent down, as in Figures 3 and 4, for attachment to the dress goods 10 in Figure 8 by clinching. The dome shaped head 5 of celluloid or other suitable plastic material is molded 70 on the backing plate when warm and pliable, and when it hardens the spurs 4 are imbedded therein so as to permanently fasten said head to said backing plate.

As illustrated in Figure 6, the circular 75 backing plate 1 may be made arched or convex, as at 6, in order to save celluloid, it being obvious that less celluloid is required to fill out the head 5 when the backing plate is thus arched than when said 80 plate is flat, as in Figure 4.

Figure 7 shows a further modification in which the slits in the backing plate 1 are arranged in the form of an X, as at 7. In this instance only two spurs 8 may be bent 85 up for engaging the plastic head, if desired. It will be noted that by making the head of celluloid or other suitable plastic substance, the spots may be manufactured much more cheaply than when the entire 90 spots are made of metal, as heretofore, and that the use of the plastic material permits of a wide range of colors being used. The plastic material may be colored before being molded on the backing plates, or coated 95 with the desired colors afterwards, if desired.

I claim:—

1. In a device of the character described, the combination with a backing plate having depending spurs for attaching to dress goods, and upstanding spurs spaced from its edge, of a plastic head conforming to said plate and in which said upstanding spurs are embedded. 100

2. In a device of the character described, the combination with a backing plate of circular form having spurs extending from its 105

periphery for engaging material to which the device is to be attached, of a head fitting over said plate and of the same size, and spurs projecting from the body portion of said plate to and embedded in said head.

3. In a device of the character described, the combination with a backing plate having depending spurs for attaching the same to dress goods, of a head overlying and conforming to the edges of said plate, and upstanding spurs on said plate embedded in said head.

4. In a device of the character described, the combination with a backing plate of convex form, of a head fitting over said convex plate, spurs extending upwardly from said convex plate and embedded in said head, and means for attaching said plate to dress goods.

5. In a device of the character described, the combination with a backing plate of convex form, of a head of plastic material fitting over said plate, spurs extending upwardly from the central portion of said convex plate and embedded in said head, and means for attaching said plate to dress goods.

6. In a device of the character described, the combination with a backing plate of convex form, of a head fitting over said plate, spurs extending upwardly from the central portion of said plate and embedded in said head, and other spurs on the edges of said plate for attaching the device to dress goods.

7. In a device of the character described, the combination with a backing plate having crossed slits in its central portion and the material between said slits bent upward to form upstanding spurs, of a head fitting over said plate and having said spurs embedded therein.

8. In a device of the character described, the combination with a backing plate having crossed slits in its central portion and the material between said slits bent upward to form upstanding spurs, of a head fitting over said plate and having said spurs embedded therein, and depending spurs on the edges of said plate for attaching the device to dress goods.

In testimony whereof I have signed my name to this specification.

EDWARD CULOTTA.
